UNITED STATES PATENT OFFICE.

CHARLES L. LIVINGSTON, OF AURORA, ILLINOIS.

DOOR-BELL.

SPECIFICATION forming part of Letters Patent No. 349,437, dated September 21, 1886.

Application filed June 21, 1886. Serial No. 205,828. (No model.)

To all whom it may concern:

Be it known that I, CHARLES L. LIVINGSTON, of Aurora, in the county of Kane and State of Illinois, have invented certain new and useful Improvements in Door-Bells; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to that class of door-bells in which the spindle is turned upon its axis in order to ring the bell, instead of being pulled outward from the door; and it consists, mainly, in combining with such a spindle and with a bell an escapement mechanism, as hereinafter set forth, and whereby the hammer may strike one or any desired number of blows to each movement or turn of the spindle, and in other particulars presently to be stated.

In the drawings, Figure 1 is a side view showing my improvements as applied to a door. Fig. 2 is a front view, the gong being removed; Fig. 3, a vertical central section; Fig. 4, an arrangement in which the escapement-wheel is the only one employed.

A is the rotating spindle, passing through the wood-work B of a door or door-frame, and C a milled disk secured on the spindle, and serving to rotate it; but it is evident that a crank, wheel, or any other handle which will serve to turn the spindle on its axis may be used instead of the disk. The spindle is prevented being pulled out by any appropriate stop, or by a pin, d, inserted therein at the inside of the door. The bell or gong E, screwed to the inner end of the spindle, also serves to prevent the spindle being pulled away from the door.

On the inside of the door or frame is fastened a bottom plate or base, F, for supporting the mechanism, and on which plate are mounted several posts or standards, g, on which is secured a top plate, H, and in these plates the spindle A, as also the spindles of the escapement-wheel I, and of the pallet K,

have their bearings. To the spindle of the escapement is connected the arm L of the hammer M.

On the spindle A is rigidly secured a small circular rack, N, and a large toothed gear, O, 55 is placed on the same spindle, but not permanently fastened to it, and so that when the spring-pawl p on the gear O is in engagement with the teeth of the rack, as shown, and the spindle is turned to the right, the 60 rack must rotate the large gear O, which then causes the small lantern-wheel Q on the spindle of the escapement-wheel to revolve rapidly, and thus to operate equally rapidly the pallet and the hammer; but when the spindle 65 A is turned to the left, the escapement clutch or pallet prevents the escapement-wheel from revolving, and the gear O is locked and the rack slips past its pawl without obstruction. It will now be evident that depending upon 70 the number of teeth in the escapement-wheel, or on the number of pins in the lantern-wheel, or on the number of teeth in the gear O, or on all combined, (and which teeth may be as few or many as desired,) the rapidity 75 of the hammer-strokes will be determined; and it will be also evident that the gears may be more than shown, if in some cases it be desired to still further multiply the number of strokes; or, if desired materially to lessen the 80 number, then the large gear O may be omitted, and the escapement-wheel may be placed on the spindle in its stead, the pallet being of course so located as to engage with it. (See Fig. 4.)

It will be evident that any ordinary pinion or gear may be substituted for the lantern-wheel Q. The spindle may of course be made to fit any thickness of door or frame, substantially the same as in a door-knob. The bell 90 itself may be applied to rotate with the spindle, or not, as desired.

The entire device is simple, easily attached, reliable, and durable.

I claim—

1. The combination and relative arrangement, as shown and described, of a door bell or gong, a rotating spindle provided with a disk or its described equivalent, serving to turn it on its axis and to actuate the hammer, and 100

an escapement mechanism actuated by such rotating spindle and serving to operate the hammer.

2. In combination, the rotary spindle A, the gear O, rack N, spring-pawl p, gear Q, or its described equivalent, escapement I, pallet K, hammer, and gong or bell, all substantially as and for the purpose set forth.

3. The described combination of parts, and to operating as set forth, namely: the spindle

A, having a rotary but no endwise movement, the gear O, loosely supported on said spindle, rack N, fast on said spindle, spring-pawl p on the gear O and engaging with rack N, lantern-wheel Q, escapement-wheel I, pallet K, arm L 15 and its hammer, and the gong or bell.

CHARLES L. LIVINGSTON.
